(57) CLAIM

The ornamental design for a dirt cup for a vacuum cleaner, as shown and described.

DESCRIPTION

FIG. 1 is a perspective view of a dirt cup for a vacuum cleaner showing our new design;

FIG. 2 is an exploded perspective view of the dirt cup and its associated components;

FIG. 3 is a perspective view of the dirt cup alone;

FIG. 4 is a top plan view thereof;

FIG. 5 is a left side elevational view thereof;

FIG. 6 is a right side elevational view thereof;

FIG. 7 is a bottom plan view thereof;

FIG. 8 is a rear elevational view thereof; and,

FIG. 9 is front elevational view thereof.

The vacuum cleaner parts shown in broken lines in FIGS. 1 and 2 are shown for illustrative purposes only and form no part of the claimed design.
